TELEPHONE SYSTEM

Clarence E. Lomax, Chicago, Ill., assignor to
 Automatic Electric Laboratories, Inc., Chicago,
 Ill., a corporation of Delaware

Application July 21, 1944, Serial No. 545,928

19 Claims.

(Cl. 179—31)

This invention relates in general to telephone systems, but more particularly to small inter-communicating or house systems of the trunk connected type, with secret service; and the primary object of the invention lies in the provision of new and improved circuit arrangements utilizing simple standard mechanisms, which do away with the need for any mechanical locking, interlocking, or releasing of calling keys.

A particular feature of this invention therefore relates to the improved circuit arrangements whereby standard non-locking push keys or lever keys of a very simple type are used for establishing a call, thus eliminating the need for complicated and delicate locking or interlocking mechanisms for these keys, either with relation to one another, or with relation to the hook-switch or cradle switch of the telephone, such mechanisms being usual with most intercommunicating systems.

Another feature of the invention relates to the circuit arrangements permitting the use of any standard telephone in lieu of some special form of instrument, as is generally required in this type of system. In the system herein described, the only external switching function required of the telephone, is to close or open the two-conductor line leading from the instrument, when the receiver or handset is removed or replaced, at both calling and called stations.

Still another feature of the invention relates to the simple manner in which all selective switching or calling keys are rendered ineffective by removing operating battery therefrom while a call is in progress, in order to prevent cutting in on an established connection, and thereby to provide secret service.

Another feature is the arrangement whereby either a calling or called party can re-ring the other party by pressing only the ringing key, if said other party should hang up prematurely.

Still another feature is that whereby a locked out station, on attempting a call to a busy station, operates the signal at the wanted station to indicate that a call is waiting.

A further feature is the provision of means at certain special stations permitting such a station to cut in on an established connection, or "over-ride" the lockout.

An additional feature permits several selective calling keys to be operated momentarily to set up a conference call, whereupon a single operation of the ringing key will simultaneously ring all stations connected to the conference circuit. A party to a conference call can hang up to leave

the conference, and later re-connect by merely again removing the receiver.

Further features and objects of the invention will be apparent from the following description, reference being made to the accompanying circuit drawing, in which the extreme simplicity of the arrangement is immediately apparent.

With reference to the drawing, which represents a schematic or diagrammatic illustration of the invention, equipment and circuits for only three stations A, B, and C are shown, as being sufficient to permit the invention to be properly described and understood. Stations B and C are represented as being purely local or intercommunicating stations, while station A shown at the upper left, provides for access to a central exchange CX. It will be understood of course that the number of stations possible in practice, would be limited chiefly by the traffic requirements, particularly as related to the use of a single intercommunicating trunk.

Each station is provided with a direct current self-interrupting signal, such as 67, actuated over a separate conductor. This signal may be either a bell or a buzzer, although a bell is the preferred embodiment. Almost any type of standard telephone may be used, since the principal function of this telephone, besides permitting conversation, is to close and open the subscriber's line when the receiver or handset is removed or replaced. A ringer is not required, but if furnished, will have no effect on the operation.

Each station is also provided with an individual select key or call key S1, S2, etc., for each station in the system, and a single ringing or signalling key R. These keys are simple non-locking push buttons, having only two pairs of make contacts (4 springs) for the select keys, and a single pair of make contacts (2 springs) for the ringing key.

It will be understood however that the invention is not limited to the use of push buttons, and that any other form of non-locking key could be used, without departing from the spirit of the invention, which lies primarily in the circuit arrangement. Push keys represent merely the preferred embodiment, because of their low cost, small size and convenience in use.

Station A shows additional equipment in the form of a single locking key T which permits connecting the telephone 15 at this station to a central office trunk, represented by conductors 40 and 41. An alternating current ringer 43 with a condenser 42 in series, is also shown connected across the incoming end of this trunk, in order

to provide a signalling means for incoming calls from the central exchange CX. This is done because of the fact that the station telephone, even were it equipped with a ringer, is completely disassociated from the central office trunk when engaged on a local call. Station A also shows how the "home" select key may be arranged to permit a special station to break in on an established connection, should it be desired to do so. To provide this service, it is only necessary to wire up the "home" key S1 as indicated by the dotted lines 11 and 12. Otherwise the "home" key if provided would be left unwired, as shown by key S2 at station B, and key S3 at station C.

In addition to the foregoing station equipment, a small group of relays is also required, including an individual switching relay SW1, SW2, etc., for each station of the system, plus three common relays comprising a battery feed relay 1, a ringing relay 8, and a lockout relay 9. A single local talking circuit or talking trunk is also provided, as represented by conductors 61 and 62, and the associated battery feed relay 7, access to which is under the control of the individual switching relays. A common source of current is employed, with the positive terminal grounded, for both talking and signalling purposes.

The system and the apparatus employed having been described, a detailed description of the operation will now be given, in order to provide a complete understanding of the invention.

Assuming, therefore, that the subscriber at station B desires to converse with the subscriber at station C, said subscriber B will first remove his receiver (or handset) such as 25. This will have no immediate effect, however, except to close the hookswitch contacts 26 and thus bridge the telephone across the two conductor line consisting of conductors 70 and 71 leading from the telephone to make contacts 72 and 73 on the associated SW2 switching relay.

Subscriber B then operates the S3 select key momentarily, whereupon both the SW3 and the SW2 individual switching relays operate. The circuit for the operation of SW3 is as follows: positive battery through the normally closed break contacts 44 of the lockout relay 9, conductors 45, 14 and 23, upper make contacts 21 of the S3 select key at station B, conductor 24, conductor 84, and the winding of relay SW3 to negative battery. A branch of this circuit also passes through the lower make contacts 22 of the S3 key, over conductor 69, and through the winding of relay SW2 to negative battery. It will be noted that the SW2 switching relay is wired to the bottom contact of all of the select keys at station B, so that the SW2 relay will always operate on calls from station B, no matter which select key is pressed. A similar arrangement at the other stations assures the operation of the individual switching relays at both calling and called stations on every normal local call.

The operation of the SW2 switching relay connects the line conductors 70 and 71 from station B through make contacts 72 and 73 of SW2 to conductors 61 and 62 of the common talking trunk leading to the common battery feed relay 7, which operates over this circuit and provides talking battery to the trunk through its own 70 windings. The operation of the SW3 switching relay similarly connects the line conductors 85 and 86 from station C to the talking trunk through make contacts 87 and 88 of SW3.

The operation of the battery feed relay 7 also

closes make contacts 60 which prepare a circuit to the common ringing relay 8 from all of the ringing keys in multiple. Relay 7 also completes a locking circuit for the operated SW2 and SW3 switching relays so that these latter relays will remain operated upon the release of the operated select key. This circuit is from positive battery through make contacts 58 of relay 7, conductor 63, make contacts 68 and 83 of relays SW2 and SW3 respectively, and thence through the windings of the two relays in parallel to negative battery.

Subscriber B now momentarily operates the ringing key R, which causes the operation of the common signalling relay 8 from positive battery through make contacts 20 of the ringing key, conductor 55, make contacts 60 of the battery feed relay 7, and thence through the winding of relay 8 to negative battery. Relay 8 operating, causes the operation of signals 67 and 82 at both the calling and called stations B and C. This circuit is as follows: negative battery through make contacts 50 of relay 8, conductor 51, conductor 64, make contacts 65 and 80 of the operated SW2 and SW3 relays, conductors 66 and 81, and thence through the signals 67 and 82 in parallel to positive battery. Relay 8 also closes an obvious circuit through its make contacts 59 to the common lockout relay 9, which also operates.

The lockout relay 9, upon operating from relay 8, completes a locking circuit for itself as follows: positive battery through make contacts 58 of the operated battery feed relay 7, conductor 57, make contacts 56 of relay 9, and through the winding of relay 9 to negative battery. The operation of the lockout relay 9 also opens the normally closed contacts 44, thereby removing positive battery from conductors 45 and 14 and hence from all of the select keys. The select keys are therefore rendered ineffective as long as relay 9 is operated, thereby preventing the operation of any more switching relays. In this manner, access to the common talking trunk is denied to the other subscribers, and the privacy of the established connection is preserved. The calling station can ringing the called station as often as necessary however, by re-operating the ringing key, should the latter station not answer promptly.

To answer, the called subscriber at station C merely removes the receiver or handset of his telephone, and is thereupon immediately connected through to the common talking trunk by way of line conductors 85 and 86 and make contacts 87 and 88 of the operated SW3 switching relay. No key operation of any nature is required at the called station on any intercommunicating call.

If another subscriber now attempts to make a call, the operation of the select key will be without effect, since these keys are now dead or disabled, due to the operation of the lockout relay 9, as previously explained. And when the ringing key is operated, although the common signalling relay 8 will operate, the calling station signal will not operate, due to its circuit being open at the contacts of the associated switching relay, thus providing an indication of the busy condition of the common talking trunk to the calling subscriber. Nor will the signal at the called station operate, except where the called station is one of the stations involved in the already established connection. In that case, the signal at the called station will function, since its associated switching relay is operated, and will thus give notice of the waiting call.

If, however, the station attempting the new call

is equipped for cut-in service, its "home" select key will be wired similarly to the indicated SI key at station A. In such a case, after determining the busy condition in the manner outlined in the preceding paragraph, the calling subscriber may if desired, be switched through to the common talking trunk by pressing the said "home" key momentarily. This will cause the operation of the individual switching relay associated with that station, and thus permit the new calling subscriber to converse with either or both parties to the connection. In the case of station A for instance, this circuit may be traced from direct positive battery at the ringing key, conductor 11, make contacts 10 of the SI select key, conductor 12, conductor 13, conductor 54, and through the winding of the individual "home" switching relay SW1 to negative battery. Relay SW1 upon operating, locks over an obvious circuit to the closed contacts 58 of the already operated battery feed relay 7.

Upon completion of a call, release of the equipment is obtained simply by both parties to the connection restoring their receivers, without any restoration of keys, mechanically or otherwise. It will also be obvious that this is a last party release system, since release is predicated on the restoration to normal of the battery feed relay 7 to which the other relays lock. And relay 7 cannot restore until the last party involved in a connection has restored his receiver since said relay is held operated over the line circuits in parallel. Restoration of the receiver by the first party or parties to hang up, thus has no effect on any operated relay. It is for this reason that the remaining party may recall the other party or parties prior to hanging up, if desired, merely by operating his ringing key alone. He cannot set up a new connection however without first hanging up, because of the disabled select keys. When the last party hangs up, the circuit to battery feed relay 7 is opened and this relay restores, unlocking lockout relay 9 and the operated switching relays, which also restore, and make the common talking trunk available for the next call.

A conference may be called by any subscriber, merely by removing the receiver in the usual way, and then momentarily operating the individual select keys of all of the subscribers wanted in the conference, before pressing the ringing key. This will cause the operation of the calling station's switching relay, as well as the individual switching relays of the various called stations. The common battery feed relay 7 operates upon the operation of the first select key, as previously explained, and provides the usual locking circuit for the various relays as they operate, through its make contacts 58. If now the ringing key is operated by the calling subscriber, the common ringing relay 8 will operate as previously described, and will cause the signals of all of the wanted stations to operate simultaneously. Lockout relay 9 also operates at this time and locks up as before, in order to exclude the other subscribers, and insure the same degree of privacy for a conference connection as for a regular two party connection. As each station answers by removing the receiver in the usual manner, it is immediately connected to the common talking trunk, as previously described, with relay 7 furnishing talking battery to all stations in multiple. Ringing may be repeated as often as necessary, and if one of the parties should leave the conference, he can be recalled by any of the remaining parties merely by the operation of the ringing

key. This will of course operate the signals at all of the conference stations.

The provision of a locking T key at any station, as shown at station A in the drawing, permits a subscriber at such a station to connect his telephone to a trunk such as indicated by conductors 40 and 41 leading to a central exchange CX. This might be any regular type of common battery exchange, automatic or manual, public or private.

This T key, being of the locking type, may be left normally switched to the central office trunk or to the intercommunicating system circuit, as desired, depending on the traffic needs. To make an intercommunicating call however, the T key should be operated to connect the telephone instrument to the local circuit as represented by conductors 52 and 53, before any select key is operated. This is necessary in order to provide a circuit for battery feed relay 7, whose operation is required as previously explained, at the time the individual switching relays operate, in order to provide the necessary locking circuits.

When the T key is in a position to connect the line from the telephone to the central office trunk, a call to the central office is made by merely removing the receiver and requesting the connection desired when the operator answers, or by dialing, if the central office is an automatic exchange, and if no operator is provided.

Incoming calls from the central exchange will cause the operation of the standard ringer 43 bridged across the central office trunk at this station, and are answered merely by removing the receiver and operating the T key, provided the latter is not already in the correct position.

The invention having now been fully described, what is considered new and is desired to be protected by Letters Patent, is set forth in the following claims.

What is claimed is:

1. In a telephone system, a plurality of subscribers' lines, a talking trunk common to said lines, a group of relays, a plurality of non-locking selective switching keys associated with each of said lines for controlling the operation of said relays, means controlled by the operation of certain of said relays for connecting both called and calling subscribers' lines to the common talking trunk; a signalling key associated with each of said subscribers' lines, means responsive to the operation of said signalling key to signal the called line, and means also responsive to the operation of said signalling key to prevent other subscribers from completing connection with the common talking trunk.

2. In a telephone system, a plurality of subscribers' lines, a talking trunk common to said lines, a group of relays, a plurality of non-locking selective switching keys associated with each of said lines for controlling the operation of said relays, means controlled by the operation of certain of said relays for connecting both called and calling subscribers' lines to the common talking trunk; a signalling key associated with each of said subscribers' lines, means responsive to the operation of said signalling key whereby both called and calling lines are signalled simultaneously, and means also responsive to the operation of said signalling key for preventing other subscribers from completing connection with the common talking trunk while it is engaged.

3. In a telephone system a plurality of subscribers' lines each including a telephone, a talking trunk common to said lines, a group of re-

lays; a plurality of non-locking selective calling keys associated with each of said lines for controlling the operation of said relays; means controlled by the operation of certain of said relays to connect both called and calling subscribers' lines to said common talking trunk; a signalling key associated with each of said lines, means responsive to the operation of said signalling key for signalling the called subscriber, means also responsive to the operation of said signalling key for excluding other subscribers from the completed connection; and means whereby the called subscriber answers and is connected to the common talking trunk by merely removing the receiver or handset from said telephone.

4. In a telephone system, a plurality of subscribers' lines each including a telephone set, a talking trunk common to said lines, a group of relays; a plurality of non-locking selective calling keys associated with each of said lines for controlling the operation of said relays, means controlled by the operation of certain of said relays for establishing a connection between both called and calling subscribers' lines and said common talking trunk; a signalling key associated with each of said lines, means controlled by said signalling key for signalling the called subscriber, means also controlled by said signalling key for excluding other subscribers from the connection; means whereby the called subscriber answers and is connected to the common talking trunk merely by removing the telephone receiver or handset of said telephone set, and means whereby the connection is released merely by both subscribers replacing their receivers or handsets of their respective telephone sets.

5. In a telephone system, a plurality of subscribers' lines each including a telephone, a talking trunk common to said lines, a group of relays; a plurality of non-locking selective calling keys associated with each of said lines for controlling the operation of said relays, means controlled by the operation of certain of said relays for connecting both called and calling subscribers' lines to the common talking trunk; means for signalling the called subscriber and at the same time locking out the other subscribers from the common trunk until the connection is released, means whereby the connection is released by both subscribers restoring their receivers, and means whereby either subscriber may recall the other merely by a momentary actuation of the normal signalling means, should said other subscriber have restored his receiver prematurely.

6. In a telephone system, a plurality of subscribers' lines, an intercommunicating trunk common to said lines, a group of relays, a plurality of non-locking selective calling keys associated with each of said lines for controlling the operation of said relays, means controlled by the operation of certain of said relays for establishing a connection between both called and calling subscribers' lines and said common intercommunicating trunk; means for signalling the called subscriber and at the same time excluding other subscribers from the said connection, and means whereby an attempted call from such an excluded subscriber to one of the parties to said connection, will cause the operation of the called subscriber's signal, to indicate a waiting call.

7. In a telephone system, a plurality of subscribers' lines, an intercommunicating trunk common to said lines, a group of relays, a plurality of non-locking selective calling keys associated with each of said lines for controlling the oper-

ation of said relays, means controlled by the operation of certain of said relays for connecting both called and calling subscribers' lines to said common intercommunicating trunk; a signalling key and a signal associated with each of said lines, means controlled by said signalling key whereby both calling and called subscribers' signals are operated simultaneously, means also controlled by said signalling key to exclude the other subscribers from the intercommunicating trunk while it is busy, and means whereby such an excluded subscriber upon attempting a call, is advised of the busy condition by the failure of operation of said excluded calling subscriber's signal.

8. In a telephone system, a plurality of subscribers' lines, a common talking trunk, a group of relays; a plurality of non-locking selective calling keys associated with each of said lines for controlling the operation of said relays, means controlled by the operation of certain of said relays for connecting both called and calling subscribers' lines to said common talking trunk; a signalling key associated with each of said lines, means responsive to the operation of said signalling key to signal the called subscriber, means also responsive to the operation of said signalling key for excluding other subscribers from the common talking trunk while it is engaged; and means whereby one or more special stations may establish connection with said trunk even while it is engaged, should they desire.

9. In a telephone system, a plurality of subscribers' lines, a common talking trunk, a group of relays, a plurality of non-locking selective calling keys associated with each of said lines for controlling the operation of said relays, means controlled by the operation of certain of said relays for connecting both called and calling subscribers' lines to said common talking trunk; a signalling key associated with each of said lines, means responsive to the operation of said signalling key for signalling the called subscriber; means also responsive to the operation of said key for excluding other subscribers from the common trunk while it is busy; and means whereby one or more special stations may establish connection with the common trunk even while it is busy, while maintaining the exclusion therefrom of the remaining subscribers.

10. In a telephone system, a plurality of subscribers' lines, a common talking trunk, a group of relays, a plurality of non-locking selective calling keys associated with each of said lines to control the operation of certain of said relays; a signalling key associated with each of said subscribers' lines, means responsive to the operation of certain of said selective keys for operating certain of said relays for connecting several of said lines to the common trunk at one time in a conference connection, means responsive to the operation of said signalling key for signalling all of such connected lines simultaneously, and means also responsive to the operation of said signalling key for excluding the other subscribers from said conference connection.

11. In a telephone system, a plurality of subscribers' lines, a common talking trunk, a group of relays, a plurality of non-locking selective calling keys associated with each of said lines to control the operation of certain of said relays; a signalling key associated with each of said lines, means responsive to the operation of certain of said selective keys for operating certain of said relays for connecting three or more of said lines to the common trunk at one time.

in a conference connection, means responsive to the operation of said signalling key for signalling all of such connected lines simultaneously, and means to permit each called conferee to answer and be connected to the common trunk merely by lifting his receiver and whereby any conferee can leave and re-join the conference merely by restoring and later again removing his receiver.

12. In a telephone system, a plurality of subscribers' lines, a common talking trunk, a group of relays, a plurality of non-locking selective calling keys associated with each of said lines to control the operation of certain of said relays; a signalling key associated with each of said lines, means responsive to the operation of certain of said selective keys for operating certain of said relays for connecting several of said lines to the common trunk at one time in a conference connection, means responsive to the operation of said signalling key at the calling line for signalling all of such connected lines simultaneously, means whereby each called conferee joins the conference by merely removing his receiver and whereby any conferee leaves the conference by merely restoring his receiver, and means whereby any of the remaining conferees may recall such absent conferee by a momentary operation of said remaining conferee's signalling key.

13. In a secret service telephone system, a plurality of subscribers' lines, an intercommunicating trunk common to said lines, a group of relays, a plurality of non-locking selective calling keys for controlling the operation of said relays, means controlled by the operation of certain of said relays for connecting both called and calling subscribers' lines to the common intercommunicating trunk; a signalling key associated with each of said subscribers' lines, means responsive to the operation of said signalling key to signal the called line, means whereby a called subscriber answers and is connected to the intercommunicating trunk merely by removing his receiver, and means associated with one or more of said subscribers' lines for answering calls from a central exchange.

14. In a secret service telephone system, a plurality of subscribers' lines, an intercommunicating trunk common to said lines, a group of relays, a plurality of non-locking selective calling keys for controlling the operation of said relays, means controlled by the operation of certain of said relays for connecting both called and calling subscribers' lines to the common intercommunicating trunk; a signalling key associated with each of said subscribers' lines, means responsive to the operation of said signalling key to signal the called line, means whereby a called subscriber answers and is connected to the intercommunicating trunk merely by removing his receiver, and special switching and signalling means associated with one or more of said subscribers' lines for making calls to and receiving calls from a central exchange.

15. In a telephone system, a plurality of subscribers' lines and stations, a talking trunk common to said lines, a relay individual to each of said lines, a non-locking calling key for each of said lines at each of said stations, means responsive to the operation by a calling subscriber of the calling key corresponding to the called subscriber's line for operating the individual relays corresponding to both calling and called subscribers' lines, circuits completed responsive to the operation of said relays for connecting both

the calling and called lines to the common talking trunk; a signal device at each subscriber's station, a signalling key at each subscriber's station, means responsive to the operation of said signalling key by the calling subscriber for operating the signal device at the called subscriber's station, and means responsive to the operation of said signalling key for preventing other subscribers from completing connection with the common talking trunk while it is engaged.

16. In a telephone system, a plurality of subscribers' lines and stations, a talking trunk common to said lines, a relay individual to each of said lines, a selecting key corresponding to each of said lines at each of said stations, an individual conductor for each of said relays, each individual conductor being multiplied to all of the utilized selecting keys at the corresponding subscriber's station and to the selecting keys corresponding to said corresponding subscriber's station at the other stations, an operate conductor common to said selecting keys, circuits including said common operate conductor completed in response to the operation by a calling subscriber of the selecting key at his station corresponding to the called line for operating both the calling and called line individual relays over their said individual conductors and multiple connections, contacts on said operated calling and called line individual relays for connecting both calling and called subscribers' lines to the common talking trunk, a battery feed relay connected to said common talking trunk operated in response to the connection of the calling subscriber's line to said trunk, contacts operated by said battery feed relay for locking each operated individual relay in operated position independently of the selective keys; a signal relay common to said subscribers' lines and stations, a signal key at each station, a circuit including other contacts of the battery feed relay for operating said common signal relay in response to the operation of the signal key at the calling subscriber's station, an individual signal device at each subscriber's station, circuits including contacts on the operated individual relays completed by the operation of said common signal relay for operating the signal devices at both calling and called stations, a lock-out relay common to said subscribers' lines and stations operated in response to the operation of said common signal relay, a locking circuit for said common lock-out relay controlled by said common battery feed relay, and contacts controlled by the operation of said lock-out relay for rendering the common operate conductor to the selective keys ineffective to complete operating circuits to any additional individual relays, in case any additional selecting keys are operated while the common talking trunk is thus engaged.

17. In a telephone system, a plurality of subscribers' lines and stations, a talking trunk common to said lines, a relay individual to each of said lines, a selecting key corresponding to each of said lines at each of said stations, circuits including an operate conductor common to all of said keys completed in response to the operation by a calling subscriber of the selecting key at his station corresponding to the called line for operating both the calling and called line individual relays, contacts on said operated calling and called line individual relays for connecting both calling and called subscribers' lines to said common talking trunk, a battery feed relay con-

neeted to said common talking trunk operated in response to the connection of said calling subscriber's line to said trunk, contacts operated by said battery feed relay for locking each operated individual relay in operated position independently of the selective keys; a signal relay common to said subscribers' lines and stations, a signal key at each station, a circuit including other contacts on the battery feed relay for operating said common signal relay in response to the operation of the signal key at the calling subscriber's station, an individual signal device at each subscriber's station, circuits including contacts on the operated individual relays completed by the operation of said common signal relay for operating the signal device at both calling and called stations, a lock-out relay common to said subscribers' lines and stations operated in response to the operation of said common signal relay, and contacts controlled by the operation of said lock-out relay for rendering the common operate conductor to the selective keys ineffective to complete operating circuits to any additional individual relays, in case any additional selecting keys are operated while the common talking trunk is engaged.

18. In a telephone system, a plurality of subscribers' lines and stations, a relay individual to each of said lines, a selecting key corresponding to each of said lines at each of said stations, a conductor individual to each of said individual relays connected to all of the said selecting keys at the corresponding subscriber's station and to each of said keys corresponding to such subscriber's line at each of the other stations, contacts on each of said individual relays comprising signalling contacts, locking contacts, and a pair of line connecting contacts terminating the corresponding subscriber's line, a common signalling conductor connected to all of said signalling contacts, a common locking conductor connected to all of said locking contacts, a common talking circuit comprising a pair of common talking conductors connected to each said pair of line connecting contacts, a common source of current, a common operate conductor normally connected to said source, and also connected to each of said selecting keys for operating the individual relays associated with both calling and called lines over their individual conductors in response to the operation by a calling subscriber of the selecting key corresponding to the called line, thereby to connect both calling and called subscribers' lines to the common talking circuit, a common battery feed relay connected to said pair of common talking conductors operated over the calling subscriber's line and the line connecting contacts of the corresponding individual relay in response to the operation of such individual relay, contacts operated by said battery feed relay for connecting the common source of current to the common locking conductor to lock the operated individual relays through their said locking contacts, signalling means individual to each subscriber's station connected to the signalling contacts of the corresponding individual relay, a signal key at each subscriber's station, a common signal circuit connected to each of said signal keys, a common signal relay, other contacts operated by said battery feed relay for connecting said common signal circuit to said signal relay and for operating said signal relay in response to the operation of any signal key, contacts operated by said signal relay for operating certain of said signalling means over circuits including said common signalling conductor and the signalling contacts of the operated individual relays, and means responsive to the operation of said signal relay for removing said common source of current from the select keys' common operate conductor to prevent the operation of any additional individual relays in case any additional select keys are operated while the common talking conductors are thus engaged.

19. In a telephone system, a plurality of subscribers' lines and stations, a relay individual to each of said lines, a select key corresponding to each of said lines at each of said stations, contacts on each of said individual relays comprising signalling contacts, locking contacts, and a pair of line connecting contacts terminating the corresponding subscriber's line, a common signalling conductor connected to all of said signalling contacts, a common locking conductor connected to all of said locking contacts, a pair of common talking conductors connected to each said pair of line connecting contacts, a common source of current, a common operate conductor normally connected to said source and also connected to each of said select keys for operating the individual relays associated with both calling and called subscribers' lines in response to the operation by a calling subscriber of the select key corresponding to the called line, in order to connect both calling and called subscribers' lines by way of said pairs of line connecting contacts to said common talking conductors, a common battery feed relay connected to said pair of common talking conductors operated over the calling subscriber's line and the line connecting contacts of the corresponding individual relay in response to the operation of such individual relay, contacts operated by said battery feed relay for connecting the common source of current to the common locking conductor to lock the operated individual relays through their said locking contacts, signalling means at each subscriber's station connected to the signalling contacts of the corresponding individual relay, a signal key at each subscriber's station, a common signal circuit connected to all of said signal keys, a common signal relay, other contacts operated by said battery feed relay for connecting said common signal circuit to said signal relay and for operating said signal relay in response to the operation of any signal key, contacts operated by said signal relay for operating certain of said signalling means over circuits including said common signalling conductor and the signalling contacts of the operated individual relays, and means responsive to the operation of said signal relay for removing said common source of current from the select keys' common operate conductor to prevent the operation of any additional individual relays in case any additional select keys are operated while the common talking conductors are thus engaged.

20. In a telephone system, a plurality of subscribers' lines and stations, a relay individual to each of said lines, a select key corresponding to each of said lines at each of said stations, contacts on each of said individual relays comprising signalling contacts, locking contacts, and a pair of line connecting contacts terminating the corresponding subscriber's line, a common signalling conductor connected to all of said signalling contacts, a common locking conductor connected to all of said locking contacts, a pair of common talking conductors connected to each said pair of line connecting contacts, a common source of current, a common operate conductor normally connected to said source and also connected to each of said select keys for operating the individual relays associated with both calling and called subscribers' lines in response to the operation by a calling subscriber of the select key corresponding to the called line, in order to connect both calling and called subscribers' lines by way of said pairs of line connecting contacts to said common talking conductors, a common battery feed relay connected to said pair of common talking conductors operated over the calling subscriber's line and the line connecting contacts of the corresponding individual relay in response to the operation of such individual relay, contacts operated by said battery feed relay for connecting the common source of current to the common locking conductor to lock the operated individual relays through their said locking contacts, signalling means at each subscriber's station connected to the signalling contacts of the corresponding individual relay, a signal key at each subscriber's station, a common signal circuit connected to all of said signal keys, a common signal relay, other contacts operated by said battery feed relay for connecting said common signal circuit to said signal relay and for operating said signal relay in response to the operation of any signal key, contacts operated by said signal relay for operating certain of said signalling means over circuits including said common signalling conductor and the signalling contacts of the operated individual relays, and means responsive to the operation of said signal relay for removing said common source of current from the select keys' common operate conductor to prevent the operation of any additional individual relays in case any additional select keys are operated while the common talking conductors are thus engaged.
